FOOT SUPPORT

Edward H. Juers, Red Wing, Minn.

Application May 16, 1949, Serial No. 93,467

5 Claims. (Cl. 36—71)

1

My invention relates generally to footwear and, more specifically, to devices designed to correct, compensate for, and alleviate distress caused by metatarsal disproportion.

I have found that, whenever there is noted a relatively short first metatarsal on the human foot, there is also a proportionate shortening of the fifth metatarsal in relation to the second, third, and fourth. This metatarsal disproportion results in an unbalance on the weight-bearing points of the forefoot, namely, the metatarsal heads and the proximal phalanges of the toes. When this anatomical arrangement exists, the major portion of the weight bearing is done by the second, third, and fourth metatarsals, and their underlying structures. This anomaly is the most common cause of metatarsalgia and the development of callouses on the plantar surface of the foot beneath the central metatarsals, as well as pronated feet and traumatic arthritis.

The primary object of my invention is the provision of a novel device which may be secured within a shoe, either at the time of its manufacture or thereafter, and which will so support the abnormal short first and fifth metatarsals as to evenly distribute the load-carrying weight of the entire foot, thereby increasing the foot comfort of the wearer as well as preventing occurrence of ailments of the above type.

Another object of my invention is the provision of a structure of the type immediately above-described which is relatively inexpensive to manufacture, which may be easily and accurately positioned within the shoe of any given wearer, and which when once applied to a given shoe will give long troublefree and comfortable service.

The above and still further objects of my invention will become apparent from the following detailed specification, appended claims, and attached drawings.

Referring to the drawings, wherein like characters indicate like parts throughout the several views:

Fig. 1 is a view in plan of the skeletal portions of a foot properly positioned on my device;

Fig. 2 is a diagrammatical side elevation, as seen from the inner side of the foot;

Fig. 3 is a view in bottom plan of my novel support applied to a removable inner-sole adapted to be placed within a wearer's shoe;

Fig. 4 is a fragmentary longitudinal section, taken on the line 4—4 of Fig. 3;

Fig. 5 is a view corresponding to Fig. 2, but showing a forefoot in plantar flexion, some parts being broken away;

2

Fig. 6 is a side elevation of the skeletal portions of the foot of Fig. 5;

Fig. 7 is a fragmentary view in front elevation of the metatarsals, being taken substantially on the line 7—7 of Fig. 6;

Fig. 8 is a plan of my novel device;

Fig. 9 is a front elevation of Fig. 8;

Fig. 10 is a view corresponding to Fig. 8, showing a modified form of the invention, some parts being broken away; and

Fig. 11 is a front elevation of the modification of Fig. 10.

Referring with greater particularity to the structure as illustrated in Figs. 1—9 inclusive, my novel device is indicated, in its entirety, by the numeral 1 and comprises a pair of spaced fingers 2 and 3 respectively which are joined at their inner ends by a transverse connecting member or portion, identified by the numeral 4. Together, the elements 2, 3, and 4, make up a supporting member for the metatarsals and other supporting bones of the forefoot, as will hereinafter be explained in detail.

Preferably and as shown, a tongue 5 projects rearwardly from the central portion of the connecting member 4. As shown, the forward ends of the fingers 2 and 3 are provided with bevelled edges 6, and the forward edge of the intermediate portion 4 is bevelled as indicated at 7. Referring particularly to Figs. 8 and 9, it will be seen that the connecting member 4 is preferably reduced in thickness for a purpose which will hereinafter become apparent.

Referring to Figs. 3 and 4, it will be seen that the rearwardly-projecting tongue 5 is adapted to be inserted through a transverse slit 8 in one of the layers of the laminated inner-sole 9. Inner-sole 9 may be built into the shoe or may be sold as an accessory in combination with my novel device. In either event, it is adapted to be snugly inserted in the shoe overlying the main sole. Supporting member 1 may be made from any relatively soft compressible material such as sponge rubber.

It might here be stated that in the normal foot the forward ends of the first, second, third, fourth, and fifth metatarsals terminate substantially in a diagonal line, defining the axis of plantar flexion, the first metatarsal being the major weight-bearing point. In the event of metatarsal disproportion, the forward ends of the second, third, and fourth metatarsals terminate substantially at the same diagonal line or axis (see line A—A of Fig. 1), whereas the forward ends of the first and fifth metatarsals terminate short of this line or axis. When a foot having

metatarsal disproportion is placed in a conventional shoe, it must, of necessity, as the fore part of the foot is flexed under load, evert or pronate, as a result of nature's attempt to make the first metatarsal the major weight-bearing point. When a pronation of the foot develops, the longitudinal arch eventually becomes depressed, resulting in a flat foot. Other undesirable effects and disabling deformities frequently result from such metatarsal disproportion, such as the development of excruciating pains, callouses on the plantar surfaces of the foot beneath the central metatarsals, and traumatic arthritis.

I have found that, by elevating and supporting certain portions of the first and fifth metatarsals and portions of other bones of the forefoot, an abnormal foot of the type above-described will be caused to function in a normal manner, thereby overcoming the tendency of the foot to pronate. Furthermore, I have found particularly in young patients, that when the foot in which metatarsal disproportion is present is properly supported by my novel structure, curative effects may be frequently expected.

When it is desired to properly position the supporting member 1 within a shoe, such as indicated by dotted lines B in Figs. 2 and 5, the tongue 5 is, as above indicated, inserted through the slit 8 in the bottom layer of a laminated inner-sole 9. The longer supporting finger, identified by the numeral 2, is positioned under the first metatarsal. When positioned, the shorter supporting finger 3 will be positioned under the fifth metatarsal. In order to obtain the full fruits of my invention, the projected forward ends of the fingers 2 and 3 are positioned so that they terminate substantially on a line coincidental with the axis of plantar flexion of the second, third, and fourth metatarsals (identified by line A—A in Fig. 1) of the foot of a given wearer. The first metatarsal is indicated by the letter c, the second metatarsal by d, the third by e, the fourth by f, and the fifth by g. Other bones in the forefoot needing identification are proximal phalanges, all five of which are identified by the letter h. When my device is properly positioned in a wearer's shoe, it will be seen, by reference to Figs. 1, 2, and 5, that the relatively thick fingers 2 and 3 underlie the forward ends of the first and fifth metatarsals c and g respectively and extend under the cooperating proximal phalanges h thereof to the axis A—A. The bevelled ends 6 of the fingers 2 and 3 permit the forward ends of the proximal phalanges h cooperating with the metatarsals c and g to comfortably rest at the same level as the phalanges cooperating with the second, third, and fourth metatarsals d, e, and f respectively. The bevelled edge 7, together with the bevelled edges 6 enable the inner-sole 9 to be molded to the necessary contours so as to provide a comfortable platform for the forefoot. When the foot is in plantar flexion, the second, third, and fourth metatarsals d, e, and f respectively, extend downwardly to a level indicated by a broken line C—C in Figs. 6 and 7. The lower forward or distal ends of the first and fifth metatarsals c and g respectively are supported, at a level indicated in Figs. 6 and 7 by the broken line D—D, by the fingers 2 and 3 respectively. This support underlies and elevates the heads of the first and fifth metatarsals b and g respectively and the portion of the proximal phalanges h cooperating therewith behind the axis A—A to a level which assures symmetrical distribution of weight for all metatarsals and

proximal phalanges. This symmetrical distribution of weight is further enhanced by the reduced thickness of the transverse connecting portion 4. The forward ends of the toes are at a common level at all times and a natural foot action is thus assured.

In the modified form of my invention illustrated in Figs. 10 and 11, the transverse connecting member 4' is made up of flat overlapping elements 10, one each formed integrally with and projecting laterally from one of the supporting fingers 2' and 3' respectively. A tongue 5' projects rearwardly from preferably both of the overlapping elements 10 for insertion into slit 8'. It should be obvious that this arrangement permits lateral adjustability of the supporting fingers 2' and 3' to accommodate feet of various widths.

If desired, the device may be impregnated with material that is opaque to X-rays so that the proper positioning thereof may be accomplished with the aid of a fluoroscope.

My device has been thoroughly tested and found to be entirely adequate for the accomplishment of the above objectives; and, while I have shown a preferred form and a single modification of my invention, it should be understood that the same is capable of further modification without departure from the spirit and scope of the invention as defined in the appended claims.

30 What I claim is:

1. A supplementary supporting member adapted to be secured within a shoe to overlie the intermediate portion of the sole thereof, said member having spaced generally forwardly-extended arms and a transverse connecting portion, said arms when properly positioned adapted to terminate substantially on a line coincidental with the axis of plantar flexion of the second, third, and fourth metatarsals of the foot of the wearer, the connecting portion of said supporting member adapted to underlie the intermediate portion of the second, third, and fourth metatarsals, said connecting member comprising overlapping elements formed integrally one each with one of said fingers in a manner to permit lateral adjustment of said fingers one with respect to the other.

2. A supplementary supporting member adapted to be secured within a shoe to overlie the intermediate portion of the sole thereof, said member having spaced generally forwardly-extended fingers and a transverse connecting portion, said fingers when properly positioned adapted to terminate substantially on a line coincidental with the axis of plantar flexion of the second, third, and fourth metatarsals of the foot of the wearer, the connecting portion of said supporting member adapted to underlie the intermediate portion of the second, third, and fourth metatarsals, said finger being of greater thickness than said transverse connecting portion.

3. A supplementary supporting member adapted to be secured within a shoe to overlie the intermediate portion of the sole thereof, said member having spaced generally forwardly-extended fingers and a transverse connecting portion, said fingers when properly positioned adapted to terminate substantially on a line coincidental with the axis of plantar flexion of the second, third, and fourth metatarsals of the foot of the wearer, the connecting portion of said supporting member adapted to underlie the intermediate portion of the second, third, and fourth metatarsals, said connecting portion having a central rearwardly-projecting tongue adapted to be inserted into a transverse slit in

an inner-sole of a shoe to anchor said supporting member against movement.

4. A supplementary supporting member adapted to be secured within a shoe to overlie the intermediate portion of the sole thereof, said member having spaced generally forwardly-extended fingers and a transverse connecting portion, said fingers when properly positioned adapted to terminate substantially on a line coincidental with the axis of plantar flexion of the second, third, and fourth metatarsals of the foot of the wearer, the connecting portion of said supporting member adapted to underlie the intermediate portion of the second, third, and fourth metatarsals, said connecting member comprising overlapping elements formed integrally one each with one of said fingers in a manner to permit lateral adjustment of said fingers one with respect to the other, one of said elements being provided with a rearwardly-projecting tongue adapted to be inserted into a transverse slit in the inner-sole of a shoe to anchor the supporting member against movement.

5. The structure defined in claim 2 in which said supporting member is formed from compressible resilient material.

EDWARD H. JUERS.
